UNITED STATES PATENT OFFICE.

HENRY LEITNER, OF CROYDON, ENGLAND.

SCREW PROPELLER.

Application filed June 8, 1925, Serial No. 35,676, and in Great Britain June 23, 1924.

This invention relates to screw-propellers, primarily intended for use on aircraft, and wherein the blades are detachable and adjustable for pitch.

5 The object of this invention is to provide a propeller blade in which various disadvantages usually existing in blades of this type of propeller are eliminated.

According to the invention I form each 10 of the blades of a propeller of a single or composite plate the two faces of which are shaped to provide the acting or working faces of the blade, the thick or root end of the shaped plate being thickened to form 15 the root of the blade by pieces applied and secured to the two faces thereof.

In a suitable arrangement for carrying 20 out the invention a plate, or a number of plates joined together to form a composite plate, or metal or non-metallic material is shaped to provide the acting or working faces of the blade, this shaping, preferably, stopping a short distance from the root end of the plate. The edges of the unshaped 25 portion of the plate are then reduced or cut away so as to present a shape in outline like the neck of a bottle. On each of the flat faces of this portion is formed an annular, straight or other shaped projection or 30 groove or recess, or a series thereof.

Two pieces of material similar to that of the blade, or of other suitable material, are shaped so that when contiguous they form 35 a body of ogival form and resemble in shape a high explosive shell or a bullet, and on their opposed flat faces are formed grooves or projections to correspond with those on the end of the shaped plate.

These two pieces are then placed on opposite 40 sides of the reduced portion of the blade and clamped thereto by rivets, screws, or the like and form the root of the blade; or they can be joined thereto by welding, brazing or the like.

45 A finishing cut is then taken from the said root to provide a journal or such ledges or grooves as are necessary for fixation to the propeller hub by engagement in a socket on the latter, two or more of such blades, 50 similarly arranged, forming a complete propeller.

To enable the invention to be fully understood I will describe it by reference to the accompanying drawing, in which:

55 Figures 1 and 2 are, respectively, eleva-

tions at right-angles of the root or butt end and a portion of the acting part of a propeller blade constructed in accordance with the invention.

Figures 3, 4 and 5 are, respectively, sections on the lines 3—3, 4—4 and 5—5, Figure 1.

Figure 6 is a view similar to Figure 1, illustrating a modification and

Figure 7 is a sectional elevation at right-angles to Figure 6.

Figures 8 and 9 are sections on the lines 8—8, and 9—9, Figure 6.

a is the simple or composite plate or block of metal or non-metallic material which is 70 shaped, to provide the working or acting faces of a propeller blade.

The shaping of the blade is not extended to the termination of the root end of the plate *a* so that the latter is left at this part, 75 indicated at *g*¹, flat on either face and is then shaped at the edges to the outline of a bottle neck, as shown, and formed, in the construction illustrated in Figures 1 to 5, with a series of projections *h*, the spaces between 80 which constitute grooves *i*. *j*, *j* are the two pieces of material, which may be the same as that of the blade, which are applied to the opposite faces of the flat part *b* to form therewith the root of the blade and which 85 pieces, if contiguous, form a body of ogival form. *k*, *k* are the projections formed on the said pieces *j*, *j* to fit into the grooves *i* of the piece *a* and *l*, *l* are the rivets by which the said pieces *j*, *j* are secured to the part *g*¹ 90 of the blade. Or, in place of the rivets *l*, screws or the like may be employed. Or, instead of the rivets, screws, etc., I may, where the parts are of metal, weld or braze 95 them together.

In the construction illustrated in Figures 1 to 5, the grooves *i* and projections *k* are formed straight and parallel, whereas in the construction illustrated in Figures 6 to 9 the said grooves and projections are of annular 100 form.

m indicates a groove cut in the root of the blade to form a journal to fit into a socket in the hub so that the blade can be adjusted therein to vary its pitch. Or, the 105 root may be ledged, grooved or formed in any other manner for the same purpose.

Claims—

1. In a screw propeller of the character described, a blade body, and means applied 110

to opposite faces of said body at the root end forming a cylindrical root, recessed circumferentially.

2. In a screw propeller of the character described, a blade body having the longitudinal edges at the root end thereof cut inwardly to provide a relatively narrow root portion, and a pair of elongated bodies secured one on either face of said root portion forming at their outer extremities, with the root portion, a cylindrical root body for engagement in a hub, substantially as and for the purpose described.
3. In a screw propeller of the character described, a blade body having the longitudinal edges at the root end thereof cut inwardly to provide a relatively narrow root portion, and a pair of elongated bodies secured one on either face of said root portion forming at their outer extremities, with the root portion, a cylindrical root body for engagement in a hub, and interlocking means between said narrow root portion and the contacting faces of said bodies, substantially as and for the purpose described.

4. In a screw propeller of the character described, a blade body having the longitudinal edges at the root end thereof cut inwardly to provide a relatively narrow root portion, and a pair of bodies of substantially ogival configuration and substantially semi-circular cross sectional design secured one against each face of said narrow root portion, the outer extremities of said bodies forming, with the adjacent blade portion, a cylindrical root designed to be mounted in a hub to permit axial rotation of the blade.

5. In a screw propeller of the character described, a blade body having a relatively

narrow flat root portion, an outwardly projecting rib formed on each face of said root portion, and a pair of elongated members extending longitudinally of the blade one against each face of said root portion, each body having the blade contacting face thereof formed to receive the adjacent rib and said bodies further having the outer extremities thereof designed to form, with the root portion, a cylindrical blade root, substantially as and for the purpose described. 45 50

6. In a screw propeller of the character described, a blade body having a relatively narrow flat root portion, an outwardly projecting rib formed on each face of said root portion and a pair of bodies of ogival configuration and substantially semi-circular cross sectional design secured one against each face of the root portion, each body having the blade contacting face formed to receive the adjacent rib and said bodies further having the outer extremities thereof designed to form, with the root portion, a cylindrical blade root, substantially as and for the purpose set forth. 65 60

7. In a screw propeller of the character described, a blade body having a relatively narrow flat root portion, a plurality of rib members formed transversely of each face of said flat root portion, and a pair of bodies of elongated ogival configuration and substantially semi-circular cross sectional design secured one against each face of the root portion, each body having the blade contacting face provided with a plurality of transverse grooves to receive the adjacent ribs and said bodies further having the outer extremities thereof designed to form with the root portion, a cylindrical blade root. 70 75

HENRY LEITNER.
